US00D584228S

(12) **United States Design Patent**
Strickland, Jr.

(10) **Patent No.:** **US D584,228 S**
(45) **Date of Patent:** **** Jan. 6, 2009**

(54) **ELECTRICAL CONNECTOR**

(75) Inventor: **Carl Craig Strickland, Jr.**, Kinston, NC (US)

(73) Assignee: **Cooper Technologies Company**, Houston, TX (US)

(**) Term: **14 Years**

(21) Appl. No.: **29/299,114**

(22) Filed: **Dec. 19, 2007**

(51) LOC (9) Cl. **13-03**

(52) U.S. Cl. **D13/133**

(58) **Field of Classification Search** D13/123, D13/133, 146, 149, 151, 154, 184, 199; 439/86, 439/180, 278, 374, 378, 380, 488-491, 527, 439/578, 585, 752, 825-828, 834, 851, 856

See application file for complete search history.

CLAIM

The ornamental design for an electrical connector, as shown and described.

DESCRIPTION

FIG. 1 is a perspective view of an electrical connector showing my new design;

FIG. 2 is a front view thereof, the rear view being a mirror image;

FIG. 3 is a top view thereof, the bottom view being a mirror image;

FIG. 4 is a left end view thereof;

FIG. 5 is a right end view thereof;

FIG. 6 is perspective view thereof, showing an alternate usage environment;

FIG. 7 is a front view thereof, the rear view being a mirror image;

FIG. 8 is a top view thereof, the bottom view being a mirror image;

FIG. 9 is a left end view thereof; and,

FIG. 10 is a right end view thereof.

The dotted lines are environmental and form no part of the claimed design. The dash-dot-dot lines indicate boundaries of the claimed design, and form no part thereof.

1 Claim, 6 Drawing Sheets
